(57) **CLAIM**

The ornamental design for an electronic device, as shown and described.

DESCRIPTION

FIG. 1 is a front perspective view of an electronic device showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an alternative bottom view thereof;

The dashed broken lines illustrate environmental structure and form no part of the claimed design.

The dot-dash broken lines represent an unclaimed boundary and form no part of the claimed design.

(Continued)

The closely spaced parallel diagonal shade lines indicate translucency.
